(57) **CLAIM**

The ornamental design for a golf club head, as shown and described.

DESCRIPTION

FIG. 1 is a front elevational view of a golf club embodying the inventive design.

FIG. 2 is a top plan view thereof.

FIG. 3 is a bottom plan view thereof.

FIG. 4 is a rear heel-side perspective view thereof.

FIG. 5 is a rear heel-side elevational view thereof showing further detail.

FIG. 6 is a rear toe-side perspective view thereof.

FIG. 7 is a rear elevational view thereof; and,

FIG. 8 is a heel-side elevational view thereof.

The broken lines immediately adjacent the shaded areas represent the bounds of the claimed design, while all other broken lines are directed to environment and are for illustrative purposes only; the broken lines form no part of the claimed design.

1 Claim, 4 Drawing Sheets

FIG. 1

FIG. 2

FIG. 3

FIG. 4

FIG. 5

FIG. 6

FIG. 7

FIG. 8
